UNITED STATES PATENT OFFICE.

JAMES WILKINSON, OF PROVIDENCE, RHODE ISLAND, ASSIGNOR TO
WILKINSON TURBINE COMPANY, A CORPORATION OF ALABAMA.

GOVERNING MECHANISM FOR TURBINES.

No. 825,999.

Specification of Letters Patent.

Patented July 17, 1906.

Application filed November 2, 1905. Serial No. 285,622.

To all whom it may concern:

Be it known that I, JAMES WILKINSON, a citizen of the United States, residing at Providence, in the county of Providence and State of Rhode Island, have invented new and useful Improvements in Governing Mechanism for Turbines, of which the following is a specification.

My invention relates to an improvement in controller mechanism for fluid-motors, and particularly elastic-fluid turbines, and has for its object to perfect in its simplest and most efficient form a safety valving and auxiliary governing means for the motor.

The safety-valve means now in general use are such as operate only under abnormal conditions. They may be operated automatically by the pressure, tripped by the governor, or brought into service by devices which operate under predetermined conditions. All such safety-valve means are unreliable for the reason that they operate only at long intervals, and there is no means of indicating at any given time whether they have not stuck or become otherwise inoperative. No valve that is not continually exercised should be solely relied upon for safety purposes. Another objection to these constructions is that the valves have to be reset after they have operated. Also the unbalanced conditions under which the valves operate frequently causes the valve to be injured during its opening or closing movements, requiring it to be made of unnecessary strength and weight.

It is the purpose of my invention to obviate the above disadvantages by the provision of what may be broadly termed an "active" safety-valve, which functions, responsive to speed or load conditions, as a secondary controller means.

Considered more specifically, my invention may be said to comprise a safety-valve means which operates on the main supply to the turbine in conjunction with primary governor-controlled valve means, which regulate the admission of the motor fluid to the turbine, both valve means operating independently and moving responsive to speed conditions, being preferably controlled by the same speed governor. The desired results are best obtained where one or both of the valve means are operated by a relay power controlled by the governor, as this takes the work directly

off the governor and enables one valve means to assume control of the turbine in the event of injury to the other. In other words, the active speed-responsive safety-valve constitutes a secondary controller means, its movements being so correlated with that of the valve or valves of the primary controller means for the turbine-nozzles that it acts without any controlling or wiredrawing effect on the fluid-supply to the turbine or to the turbine-nozzles so long as the nozzle-valves move properly in response to governor or load conditions; but in the event that the nozzle-valves, by reason of injury or defect, attempt to admit a greater volume of fluid than the operating conditions of the turbine require this safety and secondary valve commences to throttle the main supply and assumes a wiredrawing control of the motor fluid admitted to the turbine independently of the nozzle-valves.

In the accompanying drawings I have illustrated two embodiments of my invention, in one of which both the primary controller means and the safety-valve are operated by a relay power regulated by the same governor and in the other of which the safety-valve is direct connected to the governor, while the controller means are operated through a relay-power means. If a separate speed or load-responsive device were provided for operating the controller and safety-valve means, they could be direct connected; but this is an unnecessary complication.

My invention also proposes to cover, broadly, the novel combination with a multinozzle turbine of a double-controller means, one acting independently of the other to control the opening and closing of the several supply-nozzles, preferably without wiredrawing, and the other acting upon the supply of motor fluid to the nozzles and operating, under normal conditions, without effect upon the supply, but under abnormal conditions functioning as a safety-valve by assuming a wiredrawing control of the turbine-supply. Though controlled by a speed-responsive device, I propose to so adapt the operating means for the safety-valve that it will automatically close upon breakage of the speed-responsive device or its connections therewith.

My invention further comprises the details

of construction and combination of parts hereinafter more particularly described, but is claimed without specific limitation thereto.

Referring to the drawings, Figure 1 is a 5 side elevation of the turbine broken away to show the primary and secondary governing means in section. Fig. 2 is a similar view of a modification of my invention in which one of the valve means is direct connected to the 10 governor.

Similar reference-numerals refer to similar parts in both drawings.

According to the drawings I have illustrated my invention as applied to a turbine 15 of the horizontal axial flow type comprising a supply-head 1 and a plurality of diaphragms 2, subdividing the interior of the turbine into stage-compartments, within which bucket-wheels 3 rotate. A shell 4 surrounds the diaphragms and head, and is provided with abutments to hold them in position in the manner described in my prior patents. A supply-chamber or steam-chest 5 is formed between the shell and the inner 25 casing of the turbine and communicates through a port 6 with a valve-casing 7, connecting at 8 with any suitable source of steam or other motor fluid. This valve-casing is of ordinary construction, comprising a slotted 30 bushing 9, disposed lengthwise of the casing. A valve 10 moves over ports in the shell 9, being operated by a stem 11, connected to a spider 12 in the valve, which is in the form of a cylindrical shell through which pressure 35 passes from port 8 through shell ports into the steam-chest 5. The stem 11 for operating the valve passes through an elongated packing-sleeve 13, formed integral with a plate 14, which closes an end of the valve- 40 shell, being held between the flanges 15 of the casing 7 and the flanges 16 on a cylinder 17, said flanges being connected by bolts or rivets. This stem unbalances the valve so that the supply-pressure tends to close it. A piston 18 in this cylinder is connected to the 45 stem 11 and is acted upon by a coil-spring 19, tending to move it in the direction to close the valve 10. Pressure is admitted through a passage 20, leading from a controller-chamber 21 to the cylinder to move the piston against the spring 19 and the pressure acting on the valve-stem 11. I admit the supply-pressure to this controller-chamber 21 by a passage 22, leading from casing 7 50 through the plate 14 and cylinder 17 into a circular valve-chamber 23, from which the pressure is discharged through a port 24 and jet-nozzle 25 into the chamber 21 and passage 20. To vary the impact effect of the jet 55 in the passage 20, I provide means to throttle the jet, such as a rotary valve 27, which is substantially semicylindrical in shape and operatively connected to a crank 28, which in 60 turn is adjustably connected to a rod 29, op-

erated by lever 30, pivoted on a standard 31 65 and connected to a sleeve 32 of a speed-responsive device or governor 33. The standard 31 is preferably formed integral with a bearing 34 for the governor-shaft 35, which is driven in any desired manner from the 70 main turbine-shaft 36. The bearing 34 is mounted on the bearing 37 for the turbine-shaft. A passage 38 leads from the chamber 21 and conducts the jet fluid into the turbine or to any other desired point of usefulness. 75 A port 39 admits the atmosphere behind the piston 18. As the governor moves responsive to speed changes it adjusts the valve 27 to throttle the jet-nozzle 25, thereby varying the impact action of the jet in the end of 80 cylinder 17. This produces a variable static pressure in the end of the cylinder which acts against the unbalanced condition of the valve 10, and against the piston 18, so that as the controlling-pressure rises or falls the piston 85 will be adjusted to various intermediate positions in the cylinder and accordingly the valve 10 is caused to open more or less of the ported area in the shell 9, and thereby vary the opening for the supply to the steam-chest 5. The pressure thus supplied to the steam-chest is admitted to the turbine through a plurality of nozzles 40, which connect with the steam-chest through passages 41, formed in the periphery of the head and 90 leading to the supply-bowls 42 for the nozzles. Governor-controlled valves 43, operatively connected to pistons 44, regulate the admission of pressure from the steam-chest to the nozzles. Controlling-fluid pressure 95 flows from a controller-chamber through a passage 45, which communicates by branch passages 46 with the cylinders for the pistons 44. Bonnets 47 close the outer ends of the valve-piston cylinders, which may be arranged around the head in any desired manner.

The means for regulating the valve-controlling pressure may be of any desired character, that shown in Fig. 1 forming the subject-matter of a companion application and, as briefly described, comprises a governor-shifted jet-controller device 48, into which steam flows from the chest through a passage 49, similar to 41. The steam within the controller device is discharged in a thin stream, preferably an annular jet, and acts with injector and ejector effect in a chamber which communicates, through the passage 50, with the controller-passage 45. The controller-fluid pressure after exerting its impact effect flows off through a nozzle into the turbine. The adjustment of the controller device controls the admission of steam to the nozzles 40. It is my purpose to adjust the device in response to the speed or load conditions of the turbine, utilizing the governor 33 for the safety-valve for this purpose to simplify con-

struction. The controller device 48 may be connected to the governor in any desired manner.

In Fig. 1 I show a plurality of levers serving to connect the controller device 48 to the rod 29, which adjusts the valve 27. Thus a bell-crank lever 51 transmits motion from the rod to a lever 52, pivoted at an intermediate point to a swinging lever 53, connected 10 to a slide 54, movable on a lever 55, which is pivoted to the same standard as the lever 53. The lever 55 is operatively connected to the stem 56, through which the controller device 48 is adjusted to vary its injector and ejector 15 effect. A shouldered cam-collar 57 is rotated in any suitable manner and by engaging lever 52 serves to impart an oscillatory movement through the other levers to the device 48, the governor determining the 20 point of engagement between the lever and the collar, and thereby adjusting the jet device relatively to passage 50 and regulating the pressure in passage 45 by varying the injector or ejector effect of the jet. As the 25 speed increases the arm 52 is adjusted, so that the cam lowers sleeve 54, moves device 48 outwardly, giving greater impact effect to its jet, and causing the increased pressure in passage 45 to close one or more supply-valves, 30 and vice versa, as the speed decreases. As before stated, any other suitable means may be utilized for imparting motion from the governor to the controller device, as by a direct connection, that above described forming 35 a part of my companion application aforesaid and being designed to effect a pulsatory operation of the supply-valves.

In operation the adjustments between the governor-rod 29, the valve 27, and controller 40 device 48 will be such as to cause a related control of the steam admitted to and discharged from the steam-chest 5. Thus as the valves 43 are operated by the controller device 48 to introduce any given volume of 45 steam to the turbine the valve 27 will assume a position where the steam-jet in chamber 21 will create a pressure against the piston 18, which will adjust the valve 10 to follow up the demand made upon the steam-chest 5 by 50 the nozzles. As the nozzle-supply to the turbine increases and decreases the valve 10, operating on the main supply, will open and close the supply-ports for the steam-chest so as to maintain an admission area calculated 55 to keep the supply to the steam-chest equal to the demand made thereon by the nozzles. I prefer that the valve 10 should always expose a slightly-greater port area for the admission of steam to the chest 5 than the combined area of the open nozzles. This is particularly desirable when the nozzles are pulsated, as then the steam-chest serves as a reservoir, in which the valve 10 should maintain the mean pressure so that it does not fall below 60 the point calculated to give the highest

efficiency in the nozzles. Under normal conditions, therefore, the nozzle-valves 43 will control the supply to the turbine. In case they become stuck or their mechanism is broken or becomes defective and they tend 70 to admit a greater volume of steam to the turbine than the load requires the valve 10, acting as a safety-valve and moving responsive to speed or load conditions, will then wiredraw the main supply and assume control of the turbine independently of the nozzle-valves. This is a point of great advantage, as it does not necessitate the turbine being shut down for repairs to the actuating mechanism for the nozzle-valve-controlling 80 means, nor will it be necessary to stop the turbine in case of injury to the valves themselves until repairs are ready to be made. It will be noted that the valve 10 is unbalanced 85 in its closing direction and is also acted upon by the spring 19, so that in case of the lowering of the controller-pressure in the piston-cylinder 17 the valve will immediately close, thus acting as any ordinary safety-valve. This closing action of the valve will be obtained when the governor under maximum speeds moves the valves 27 to close the port 24 or when in case of breakage of the governor or its connections to the crank 28 the latter will drop, due to its own weight or that of 90 rod 29, to a position where the valve 27 closes the passage 22, and thus causes the valve 10 to cut off the supply.

In Fig. 2 I illustrate a modification of my invention, in which the safety-valve 10 is connected to a stem 58, which passes entirely through the valve-casing 59, so that the valve is substantially balanced. The stem at its left hand end passes through a gland or stuffing-box and at its end nearest the governor 60 is provided with two longitudinal grooves 61 and 62, divided by a narrow partition 63. The right-hand end of the stem may also be packed, if desired, but not so as to interfere with the free exhaust through the 100 passage 61. The groove 61 is normally open to the atmosphere, while the groove 62 is open to the supply-pressure in the valve-casing. A reduced extension 64 of the casing in which the grooved portion of the stem is disposed is provided with a plurality of passages 65, separated at a distance substantially corresponding with the width of the partition 63. Any suitable means, such as the tongue and groove 66 and 67, are provided to maintain the grooved portion of the stem opposite the passages 65. It follows that as the stem 58 moves back and forth in the valve-casing it successively exposes the 110 passages 65 to the high pressure or the atmosphere, according to its direction of movement. As shown, these passages connect with fluid-motors 68 for operating the turbine-supply valves 69. The governor 60 is connected to the bell-crank 70 and to one end 115 120 125 130

of the stem 58. The number and arrangement of the passages 65 is such that the governor acts through the relay-power means to successively open or close them as the load on the turbine varies, and the valve 10 is so positioned on the stem 58 that it follows the governor and acts in the manner already described to reduce the ported area through which pressure flows to the turbine.

10. What I claim as new, and desire to protect by Letters Patent, is—

1. In a governing mechanism for a fluid-motor, a speed - responsive device, valve means controlled thereby for regulating the admission of fluid to said motor, and a safety-valve operating on the main fluid-supply and movable responsive to variations in the speed or load of the motor.

2. In a governing mechanism for a motor, a speed - responsive device, a plurality of valves controlled by said device and regulating the admission of fluid to the motor, a safety-valve means operating on the main supply, and means to adjust said safety-valve means responsive to the varying volume of fluid required by the motor.

3. In a governing mechanism for a motor, a primary controller means for regulating the fluid-supply in accordance with the load, and a safety-valve adapted to function as a secondary controller means when said primary controller means become defective or inoperative.

4. In a governing mechanism for a fluid-motor, a speed-responsive device, a safety-valve operating on the main supply responsive to said device, and valves independently controlled by said device and acting to regulate the admission of fluid-pressure to said motor.

5. A governing mechanism for an elastic-fluid turbine, comprising a plurality of valves controlling nozzle-passages and speed-responsive means to operate said valves without intermediate positions, which parts constitute a primary controller means, in combination with speed-responsive valve means adapted to operate as a secondary controller means and act with throttling effect on the supply to said nozzle-valves only when the latter admit an excessive supply of fluid to the turbine.

6. In a governing mechanism for an elastic-fluid turbine, speed-responsive means, valve means controlled thereby for regulating the admission of motor fluid to the turbine, and safety-valve means controlled by said speed-responsive means and adapted to vary the ported area through which motor fluid flows to said admission-valve means, in a predetermined relationship to the volume of the fluid admitted by said admission-valve means to the turbine.

7. In a turbine, a safety-valve operating

on the main fluid-supply and adapted under abnormal conditions to vary its volume substantially in accordance with the load, a plurality of nozzle-passages through which fluid is discharged against a rotary element in said turbine, valves for cutting said nozzles into and out of service, and a speed-responsive device which controls said valves independently of said safety-valve and regulates the fluid-supply under normal conditions.

8. A turbine having a steam-chest, a plurality of nozzles communicating therewith, rotating elements against which said nozzles are adapted to discharge fluid, independent valves for said nozzles, a speed-responsive device, and a relay-power means controlled thereby for operating said valves, in combination with a valve movable over the supply-port of said steam-chest and controlled by said speed-responsive device.

9. In combination with a fluid-motor having an independent primary controlling means for regulating the supply of motor-fluid, a safety-valve operating on the main supply and adapted to assume intermediate positions responsive to the changes in the speed of the motor.

10. In a fluid-motor, a speed-responsive device, and a safety-valve adapted to operate on the main supply and assume intermediate positions responsive to said device.

11. In an elastic-fluid turbine, a primary controlling-valve for an admission-passage which the motor-fluid tends to open, a safety-valve adapted to cut off the motor-fluid supply to said admission-valve, said motor fluid tending to close said safety-valve, a speed-responsive device which operates said safety-valve against said motor fluid causing it to assume intermediate positions, and a device for controlling the operation of said admission-valve which is operated by said speed-responsive device.

12. A controlling mechanism for a turbine comprising a plurality of fluid-admission valves for the turbine, motors for operating said valves, a safety-valve in a fluid-supply conduit, a motor for moving said valve with intermediate operating positions to close said conduit, and a speed-responsive device adapted to control said motor separately and adjust said safety-valve so that, in the event of injury to said fluid-admission valves, said safety-valve stands ready in a position to valve off excess motor fluid from the turbine.

13. In a governing mechanism for a turbine, a primary controller means which regulates, under the control of a speed-responsive device, the admission of motor fluid to the turbine, a safety-valve adapted to cut off the fluid-supply from said primary controller means, means, under the control of said speed-responsive device, for operating said safety - valve with intermediate positions,

the means being adapted in the event of breakage to cause said safety-valve to close automatically.

4. An elastic-fluid turbine having one or more fluid-admission ports, a speed-responsive device, valve means controlled thereby to intermittently cut off said port or ports, a supply chamber or reservoir from which motor fluid is intermittently discharged into the turbine, valve means for the admission port or ports for said chamber, and devices to move said latter valve means responsive to speed changes and without an intermittent cut-off action, as and for the purposes described.
15. An elastic-fluid turbine having a pri-

mary controller means which intermittently cuts off all or part of the supply under the control of a governing means, in combination with a secondary controller means adapted 20 to operate responsive to speed conditions and to regulate the supply by wiredrawing as contrasted with intermittently cutting off all or part thereof by said primary controller means.

In testimony whereof I have hereunto set 25 my hand in presence of two subscribing witnesses.

JAMES WILKINSON.
